UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

ICE-SCRAPER.

SPECIFICATION forming part of Letters Patent No. 727,593, dated May 12, 1903.

Application filed September 13, 1902. Serial No. 123,250. (No model.)

To all whom it may concern:

Be it known that I, FRED B. COREY, a citizen of the United States, residing at Schenectady, in the county of Schenectady, State of New York, have invented certain new and useful Improvements in Ice-Scrapers, of which the following is a specification.

My invention relates to improved means for removing the ice from such rails as the conductor-rails of the so-called "third-rail" system of electric railways.

The object of my invention is the production of a device for removing ice or sleet which forms on the top of the conductor-rail which is simple and efficient and which can be easily and cheaply replaced when worn.

The points of novelty which I think my invention possesses I have pointed out with particularity in the accompanying claims.

In the following description and accompanying drawings I have illustrated embodiments of my invention.

Figure 1 of the drawings is an elevation, partly in section, showing one embodiment of my invention. Fig. 2 is a plan view showing part of the structure shown in Fig. 1. Fig. 3 shows a somewhat-different embodiment of my invention. Figs. 4 and 5 are sectional views showing differently-constructed cutting-wheels.

In Fig. 1 the conductor-rail of a third-rail system is shown mounted on suitable insulating-supports 2. A guard-rail 3, supported by a suitable bracket 4, is shown overlying the conductor-rail. The ice-cutting wheel 5 is mounted in a bracket or supporting-arm 6, which may be made out of resilient material and which depends from the body of the vehicle 7. The ice-cutting wheel 5 is provided with a series of cutting edges 8 and may be formed out of a solid piece, as shown in Fig. 4, with the cutting edges formed in the shape of circumferential ridges or ribs upon its periphery, or it may be formed as shown in Fig. 5, where a plurality of large dished disks 9, of sheet metal, form the cutting members and are separated by disks or spacing members 10. In either event the disk is set with its axis oblique to the conductor-rail and to the

direction of travel, as best shown in Fig. 2, so that the action in breaking and removing the ice is a combined sliding and rotating one.

In the construction shown in Fig. 3 the cutting-disk is carried in an upright yoke 6', which is mounted in a member 7', carried by the vehicle. In this construction I have shown a spiral spring 12 for maintaining the disk against the rail with a suitable pressure, the yoke 6' being slidingly but non-rotatably mounted in the member 7'. With either construction the ice-scraper mechanism should be so connected to the car as to be readily removed. In the construction shown in Fig. 3 the member 7' may be hinged to the body of the car, so that when the ice-scraper is not needed it may be swung into an inoperative position.

The construction shown in Fig. 1 has certain advantages in that it can be used on a system where the conductor-rail is covered by a guard-rail, and while it is true that where the conductor is covered by such a guard-rail there will be little, if any, necessity for the use of such a scraper in practice it may frequently happen that a car on the same run will encounter both the covered and the uncovered construction of conductor-rail.

The construction of the scraper shown in Fig. 5 is especially advantageous in that when the cutting-surfaces are worn away the cutter may be taken apart and the cutting-disks 9 can be removed and replaced by new cutting-disks without scraping the rest of the wheel.

The cutting-wheels in general should be so proportioned as to contact substantially all the face of the rail. If desired, the outer disks may be made somewhat larger than the inner ones, as shown in Figs. 1 and 2, so as to contact with the upper face of the conductor-rail when curved.

By the construction shown an ice-scraper is secured which is simple and reliable and of which the parts subjected to wear are readily replaceable. By setting the cutting-disks askew the combined effect of a rotating and sliding action is obtained without the use of

gearing. This action is very desirable in breaking and removing the ice from the rail.

While I have shown and described the best forms of my invention which are now known to me, I do not intend to be limited to the exact details of construction herein shown and described.

It is easily seen that my scraper could be used on other than current-carrying rails.

10. What I claim as new, and desire to secure by Letters Patent of the United States, is—

1. In combination, a rail and an ice-remover therefor, comprising a substantially cylindrical cutter-body having circumferential cutting edges held in contact therewith

with its axis oblique to the rail, said body being free to rotate.

2. In combination, a rail, a vehicle moving in fixed relation thereto, and a rotatable rail-cleaning member carried by the vehicle and set with its axis oblique to the direction of movement of the vehicle and in such position as to contact with the rail and be frictionally rotated thereby.

In witness whereof I have hereunto set my hand this 10th day of September, 1902.

FRED B. COREY.
